UNITED STATES PATENT OFFICE.

CLARA M. BURBANK, OF LOS ANGELES, CALIFORNIA.

DESIGN FOR A WAFFLE-IRON.

59,710.

Specification for Design.

Patented Nov. 22, 1921.

Application filed April 26, 1921. Serial No. 464,705. Term of patent 14 years.

To all whom it may concern:

Be it known that I, CLARA M. BURBANK, a citizen of the United States, residing at Los Angeles, in the county of Los Angeles and State of California, have invented a new, original, and ornamental Design for a Waffle-Iron, of which the following is a specification, reference being had to the accompanying drawing, forming a part thereof, the same being a perspective view of a waffle iron showing the design.

I claim:

The ornamental design for a waffle iron, substantially as shown.

Signed at Los Angeles, in the county of Los Angeles, and State of California, this 20th day of April, 1921.

CLARA M. BURBANK.

Witness:

JAMES R. TOWNSEND.
